CLOSURE FOR RECEPTACLES

Percy M. Thorn, New Rochelle, N. Y.

Application December 19, 1935, Serial No. 55,158

4 Claims. (Cl. 221—64)

This invention relates to closures. It is an object of this invention to provide a closure of the sifter type which may be readily opened and closed and which, when in the closed position, 5 will maintain a tight closure at all times. It is a further object to provide a top of the character described which will be simple in construction and reliable in operation.

The invention accordingly comprises an article of manufacture possessing the features, properties, and the relation of elements which will be exemplified in the article hereinafter described and the scope of the application of which will be indicated in the claims.

15 For a fuller understanding of the nature and objects of the invention reference should be had to the following detailed description, taken in connection with the accompanying drawing, in which:

20 Fig. 1 is a perspective view of a top embodying the invention.

Fig. 2 is a top plan view of the base member.

Fig. 3 is a top plan view of the shutter member.

25 Fig. 4 is a top plan view of the assembled device.

Fig. 5 is an enlarged section on the curved line 5—5 of Fig. 4.

In the drawing the character B represents a 30 cup shaped base member having a side wall 11 and an end wall 12. The side wall 11 is provided with a peripheral indentation 13 for the attachment of a cap member hereafter to be described, and the end wall 12 is provided with a plurality 35 of perforations 14. Mounted upon the base member is a cup shaped cap member C having its lateral wall 9 extending down parallel to and embracing the side wall 11 of the base member, and having indentations 15 spaced approxi-

40 mately 90° apart engaging diametrically disposed indentation 13 of the base member to hold the cap member in place and against excessive axial movement in either direction. The end wall 16 of the cap member is substantially parallel to 45 and spaced from the end wall 12 of the base member to form a space for a shutter S to lie between them. This shutter S has at one end

a pin 17 fitting within a recess 18 in the base, and at the other end a pin 19 fitting within a recess 20 in the cap. The shutter member S has its contour defined by two arcs of circles whereby it may be swung from one side of the base member to the other, and with this construction it will be clear that as the cap member C is rotated by virtue of the knurled portion 10, through

a small arc, the engagement of the pins and recesses will cause the shutter to be moved from one side to the other. In one of the extreme positions of the shutter and cap member these two members are provided with openings 14a and 14b respectively, which register with the perforations 14 in the base but which will be clear that as the shutter is swung to the other position, the parts will be moved within registry with each other.

10 It will be noted that the perforations 14 are not equally spaced around the periphery of the cap. This is by reason of the fact that the shutter is pivoted at its opposite ends, and near the pivots the relative movement between the pivoted parts is much less than throughout the remainder of the surface. It follows that the openings adjacent to each of the pivots can only be closed by an extreme angular movement of the shutter about its pivots which is not desired. To 20 overcome this difficulty perforations near the pivots are omitted.

It will be further observed that the maximum relative movement between the shutter and the parts to which it is pivoted occurs along the arcs 25 of the circles having their centers at the pivots and the limit of the size of opening permissible is limited upon mutual physical movement of these parts along these circles. It follows that a greater opening can be obtained for any given 30 movement of the shutter if the openings be elongated along the axis passing through the pivots.

For the purpose of causing a completely tight joint the end walls 12 and 16 respectively may be deformed in such a manner as to press toward 35 each other over the areas immediately surrounding the openings as shown at 22 so that the area of pressure is confined to the areas where the tight joint is required.

Since certain changes may be made in the 40 above construction and different embodiments of the invention could be made without departing from the scope thereof, it is intended that all matter contained in the above description or shown in the accompanying drawing shall be 45 interpreted as illustrative and not in a limiting sense.

It is also to be understood that the following 50 claims are intended to cover all of the generic and specific features of the invention herein described, and all statements of the scope of the invention which, as a matter of language, might be said to fall therebetween.

Having described my invention, what I claim as new and desire to secure by Letters Patent is: 55

1. A closure of the character described comprising in combination a base portion and a cap portion fitting over said base portion, a shutter movable between said portions and pivoted at 5 its opposite ends to said portions having a plurality of registering openings through said portions and said shutter whereby movement of said cap portion upon the base portion will move the shutter to bring said openings in the base 10 portion, in the cap portion and in the shutter, in a position to register with each other in one position of the parts, said openings being disposed in symmetrical groups and being spaced circumferentially more distant from each other at 15 points corresponding to the position of the two pivots than between said points.
2. A closure of the character described comprising in combination a base portion and a cap portion fitting over said base portion, a shutter 20 movable between said portions and pivoted at its opposite ends to said portions there being registerable openings in said base portion, said cap portion and said shutter whereby movement of said cap portion upon the base portion will move 25 the shutter to bring said openings in the base portion, in the cap portion and in the shutter, in a position to register with each other in one position of the parts, said openings being disposed in symmetrical groups distant from the 30 pivots, each of said openings being elongated in the direction of a radius through the nearest pivot whereby the maximum opening is obtained with the minimum movement.
3. A closure of the character described comprising in combination a base portion and a cap portion fitting over said base portion, a shutter 35
- movable between said portions and pivoted at its opposite ends to said portions there being registerable openings in said base portion, said cap portion and said shutter whereby movement of said cap portion upon the base portion will move the shutter to bring said openings in the base 5 portion, in the cap portion and in the shutter, in a position to register with each other in one position of the parts, said openings being disposed in symmetrical groups distant from the 10 pivots and said openings being arranged symmetrically and concentrically upon the cap portion but with no openings near the pivots, said base portion and said cap portion having two sets of cooperating circumferential bearings of 15 limited circumferential extent to prevent relative movements of the parts along the axis in either direction, but to permit a limited rotation sufficient to move the shutter and the limiting of said bearing being sufficient to prevent further 20 rotary movement.
4. A closure of the character described comprising in combination a base portion and cap portion fitting over the base portion, each of said portions having an end wall, and a side wall, 25 a shutter fitting between the end walls and pivoted at one end to the base portion and at the other end to the cap portion, such base portion, cap portion and shutter having a plurality of openings adapted to register in one position of 30 the cap portion and the end wall of said base portion having a raised boss surrounding each of said openings to concentrate the pressure at that point.

PERCY M. THORN. 35
